UNITED STATES PATENT OFFICE.

MELVON A. MARQUETTE, OF CHICOOEE FALLS, MASSACHUSETTS, ASSIGNOR TO THE FISK RUBBER COMPANY, OF CHICOOEE FALLS, MASSACHUSETTS, A CORPORATION OF MASSACHUSETTS.

METHOD AND APPARATUS FOR CUTTING BIAS STRIPS.

Application filed August 4, 1920. Serial No. 401,277.

To all whom it may concern:

Be it known that I, MELVON A. MARQUETTE, a citizen of the United States of America, residing at Chicopee Falls, in the county of Hampden and State of Massachusetts, have invented certain new and useful Improvements in a Method and Apparatus for Cutting Bias Strips, of which the following is a specification.

10 My present invention relates to a method and an apparatus for cutting fabric on the bias, and particularly to the cutting of a succession of bias strips from a relatively long sheet of fabric.

15 It has for its object the cutting of fabric on the bias while the fabric is moving, thereby greatly increasing the output. It has for a further object the substantial elimination of moving, and especially reciprocating, parts. It has for a further object the provision of means whereby the cutting means can be renewed or replaced without stopping the machine. It has various other objects relating to improvements in the method 20 and to constructional and operating advantages which will appear from the ensuing description and the appended claims.

My invention will now be described with particular reference to the accompanying 30 drawings some of which are diagrammatic in their nature, and in which—

Fig. 1 is a diagrammatic side elevation of a device embodying my invention;

Fig. 2 is an enlarged detail showing the 35 coaction of the cutting members with the cutting roll;

Fig. 3 is a detail showing the construction of the cutter tracks at the curves;

Fig. 4 is a plan view corresponding to 40 Fig. 2;

Fig. 5 is an enlarged detail showing the cutter removing and replacing switches;

Fig. 6 is a top view of one of the cutter carriers; and

Fig. 7 is a detail of one of the switches.

Referring first to Fig. 1, a sheet of fabric 10, usually rubberized, is led from a spool 11, under a guide roll 12, and over a cutting cylinder 13. The fabric may be held in contact with this cylinder by rollers 14 and 15.

50 In passing over the cutting cylinder the fabric is severed into bias strips. These strips are cut by the mechanism which will

now be described. Arranged adjacent cylinder 13 are tracks 16 and 17, upon which run carriers 18 which engage the tracks by bearings 19 and 20. The tracks may be supported from any suitable frame by posts 21. On the curved portion of the tracks they are preferably cut away as at 22 (Fig. 3) 60 to prevent binding of the carriers. Each carrier has a bracket 23 which carries a cutter 24. This cutter is preferably a thin blade having cutting edges at 25 and 26, so that by reversing the blade a new cutting 65 edge is presented to the work. The blade may be fastened to the bracket by dowels 27 and a thumb screw 28. Bracket 23 also carries a guide finger 29, adapted to run in one of a series of spiral grooves 30 in the surface of cylinder 13 and preferably bulged near the top to assure a good bearing surface in the groove while the portion of the flange adjacent to the fabric is as thin as the stresses allow in order to present minimum interference with the edges of cut fabric. As will be apparent from Fig. 4, the rotation of cylinder 13 will cause carriers 18, due to their engagement with grooves 30, to progress across the roll, their motion being restricted by the guides to a line parallel with the axis of the roll. In order that the blades will lie in the grooves during the above described travel of the carriers the brackets 23 are angularly mounted, as clearly appears from the drawings.

In order to return the carriers to the initial side of the cylinder a belt or cord 31 is disposed about pulleys 32. This belt engages fingers 33 frictionally pressing against the belt, and serving to hold the carriers to the belt for motion therewith when they are not restrained by the grooves 30. The pulleys are driven, as by gearing 34 connected to the cutting cylinder, at such a speed that the carriers will travel along the return path at a higher speed than the rate at which they are fed by the grooves. This results in a piling up of the carriers at the entrance side of the cylinder; so that one is always ready to pass into a groove when the leading end thereof is in position. It will be noticed, also, that the feed of the carriers during the cutting is controlled positively by the grooves in the cylinder, the belt slipping through the friction clips during this opera-

tion. A guide 35 may be located by suitable brackets so as to maintain the engagement of the belt and clips.

The sheet thus cut into bias bands is led by a guide 36 and a roll 54 which directs it to the delivery device, which may be of any desired type. If the fabric has been coated with rubber before being cut, however, it is necessary to provide a "liner," so-called, of uncoated fabric to prevent adjacent rubber surfaces coming in contact. In the drawings this liner is indicated at 37, and passes over guide-rolls 38 and 39, when it again meets the rubberized fabric, now cut into bias strips, and serves as a support therefor. A gravity tension roll 55 serves to keep the liner taut. The liner and bias cut strips are conveniently wound on a roll or spool 40, which may be rotated by a belt 41 mounted on pulleys 42 driven by any suitable mechanism.

It is desirable to provide means for allowing the carriers to be removed from the track, and carriers having sharpened blades substituted, without stopping the machine. For this purpose switches are preferably provided, as will now be described. In Fig. 5 these switches are shown in position to remove carriers from the track. The moving switch consists of a double track 43 corresponding to tracks 16 and 17, pivoted at 44 and preferably having a removable stop 45. Tracks 16 and 17 have pivoted sections 46 which are pushed out of line by the movement of the switch in position. The pivoted sections 46 may conveniently be constructed as shown in Fig. 7, being pivoted at 47 to the main track and having a suitable leaf spring 48 serving to hold the pivoted section in alignment with the main track when the switch is not being operated. The end of the pivoted section is preferably shaped as at 49 to permit it to seat firmly in alignment with the main track. The switch for inserting carriers with sharpened blades may be constructed with a fixed track 50, and a pivoted section 51, of the main track, which may be constructed as described for section 46.

The construction above described lends itself readily to adjusting the width of the bias strips to any one of a predetermined number of widths. This may be done by providing the cylinder 18 with extra grooves 52, those not in use being closed as by plates 53 to prevent entrance of carriers. If it is not desired to have this adjustable feature the carriers may be controlled by a positively driven chain.

I claim:

1. The method of cutting bias strips from a relatively long sheet of fabric, consisting in supporting the fabric on a moving surface, making repeated bias cuts from edge to edge of the fabric by passing a cutting

member across the moving surface at right angles to its direction of movement, and removing from the surface the bias strips thus cut.

2. The method of cutting bias strips from a relatively long sheet of fabric consisting in moving the sheet continuously in the direction of its length, and moving a succession of cutting members across the strip in a path substantially normal to the direction of movement of the sheet.

3. The method of cutting bias strips from a relatively long sheet of fabric consisting in moving the sheet in the direction of its length, and moving a succession of cutting members across the strip at such an angle that the resultant of the motions of the strip and cutting members will produce the desired angularity in the bias strip.

4. The method of cutting a relatively long web of fabric on the bias consisting in moving said web in contact with the surface of a rotating cylinder, and passing a cutting member axially of the cylinder and in contact with the web to sever the latter on the bias from edge to edge while the cylinder and web are moving.

5. An apparatus for cutting fabric on the bias comprising a cylinder, means for guiding a web of fabric over the cylinder, a carrier fitted with a cutting blade and movable axially of the cylinder from one edge of the fabric to the other, and means for rotating the cylinder and reciprocating the carrier in synchronism.

6. An apparatus for cutting fabric on the bias comprising a rotatable cylinder, means for guiding a sheet of fabric over the cylinder, a series of carriers fitted with cutting blades movable axially of the cylinder, and means for moving said carriers successively and in synchronism with the cylinder.

7. An apparatus for cutting fabric on the bias comprising a cylinder having helical grooves therein, means for guiding a sheet of fabric over the cylinder, a series of carriers having cutting blades, and having means for engagement with said grooves, guides for directing said carriers adjacent the cylinder and parallel with the axis thereof and for returning the carriers to the initial end of the cylinder, and means for moving the carriers back to the initial end of the cylinder after they leave said grooves.

8. An apparatus for cutting fabric on the bias comprising a cylinder having helical grooves therein, means for guiding a sheet of fabric over the cylinder, a series of carriers having cutting blades, and having means for engagement with said grooves, guides for directing said carriers adjacent the cylinder and parallel with the axis thereof and for returning the carriers to the initial end of the cylinder, and means

for moving the carriers back to the initial end of the cylinder after they leave said grooves and switches in said guides whereby certain of said carriers may be inserted or removed without stopping the operation of the machine.

9. An apparatus for cutting fabric on the bias comprising a cylinder having helical grooves therein, means for guiding a sheet of fabric over the cylinder, a series of carriers having cutting blades, and having means for engagement with said grooves, guides for directing said carriers adjacent

the cylinder and parallel with the axis thereof and for returning the carriers to the initial end of the cylinder, and means for moving the carriers back to the initial end of the cylinder after they leave said grooves, said last-named means being constructed and arranged to move at a higher speed than the feed of said grooves, and to have slipping engagement with said carriers, whereby said carriers are pressed against the initial end of the cylinder and held in readiness to be received by the grooves.

MELVON A. MARQUETTE.
